UNITED STATES PATENT OFFICE.

FRANK H. QUADE, JR., OF FRESNO, CALIFORNIA.

AUTOMATIC FEED-CONTROLLING MECHANISM FOR PRINTING-MACHINES.

1,269,305.

Specification of Letters Patent. Patented June 11, 1918.

Application filed May 15, 1917. Serial No. 162,778.

To all whom it may concern:

Be it known that I, FRANK H. QUADE, Jr., a citizen of the United States, residing at Fresno, in the county of Fresno and State of California, have invented certain new and useful Improvements in Automatic Feed-Controlling Mechanism for Printing-Machines, of which the following is a specification.

10 This invention relates to printing machinery and has special reference to that type of printing machines in which letters or circulars have portions printed through ribbons so as to attain the effect of type-written matter. The primary object of the present invention is to provide simple means whereby the feeding of the paper to the printing mechanism may be automatically controlled so that the impression rollers or 20 roller will not be lowered to the type bed unless a sheet of paper is in proper position. A further object of the invention is to provide means whereby the engagement of the paper and the feeding of the same through 25 the printing mechanism may be accurately timed, and a still further object of the invention is to provide improved means for restraining the paper against premature movement to the printing roller or platen. 30 Another object of the invention is to provide means whereby the ribbon will be prevented from feeding until after the end of a stroke of the type bed. Other objects of the invention will appear as the description of the same proceeds and the invention resides in certain novel features which will be particularly pointed out in the claims following the detailed description.

The invention is illustrated in the accompanying drawings, in which—

Figure 1 is a perspective view of so much of a printing machine as is necessary to illustrate the present improvements;

Fig. 2 is a longitudinal section through the platen, the paper-feeding rollers, and the coöperating parts arranged to prevent the passage of paper to the printing mechanism;

Fig. 3 is a similar view showing the parts arranged to permit feeding of the paper;

Fig. 4 is a detail view showing the manner of supporting one side of the frame in which the rollers are mounted;

Fig. 5 is a detail view of a tension device for the upper feed roller;

55

Fig. 6 is a side elevation of a portion of the controlling mechanism;

Fig. 7 is a detail elevation of a portion of the controlling mechanism;

Fig. 8 is a view similar to Fig. 6 but showing the parts in a different position;

Fig. 9 is a detail bottom plan view;

Fig. 10 is a detail view of the feeler.

The main frame 1 may be of any convenient or preferred construction and the type bed 2 is mounted to reciprocate longitudinally upon the frame. A main driving or oscillatory lever 3 is provided below the type bed and is connected therewith to actuate the same, the said lever being vibrated 70 through any convenient form of gearing, which is not illustrated. A rock shaft 4 is mounted upon the main frame at one end thereof, and is provided intermediate its ends with a crank 5 which is connected by a 75 link 6 with the main lever 3, as shown. Upon one end of this rock shaft is a crank 7 to the upper end of which is pivoted one end of a connecting bar 8 disposed longitudinally of the frame adjacent the side of the 80 same.

The platen or impression roller 9 and the feed rollers 10 and 11 are mounted between the side plates 12 and 13 which are supported on the side members of the main 85 frame 1. The plate 12 is provided at its lower edge with eyes 14 through which and similar eyes on the main frame a pin 15 is inserted to hingedly connect the said side plate with the main frame. The side plate 90 13 rests upon the upper edge of the side member of the main frame and carries a dowel pin 16 which is adapted to enter a suitable recess in the upper edge of the main frame and thereby properly position 95 the side plate thereon. The said side plate is further provided with threaded sockets 17 in its lower edge which may be engaged by the upper threaded ends of screws 18 fitted in the side member of the main frame 100 in position to engage said sockets, as clearly shown in Fig. 4. Intermediate their ends, these screws 18 are reduced in diameter, as shown at 19, thereby providing grooves or ways in which are engaged pins or studs 20 105 on the main frame so that the screws will

be held in proper position to engage the sockets and will be limited in their movement and prevented from dropping when released from the sockets. This method of mounting the said feeding and presser rollers upon the main frame facilitates access to the type bed when it is necessary to make any quick changes in the form.

The platen or impression roller 9 is held low and has an eccentric 21 extending longitudinally through it, the said eccentric being journaled in the side plates and held against endwise movement by pins or screws 22 inserted vertically into the plates 12 and 13 and engaging the journals of the eccentric in a well known manner. Jam nuts 23 upon these screws or pins maintain them in proper position. One end of the eccentric 21 projects through the side supporting plate 13 and is equipped with a pinion 24 which is engaged by a rack as will be presently set forth, so that turning of the eccentric may be effected to raise or lower the impression roller. At the opposite side of the machine, the impression roller is equipped with a gear 25 adapted to mesh with a rack 26 on the type bed so that reciprocation of the type-bed will cause rotation of the roller and a consequent feeding of paper through the machine. Between the impression roller and the rear ends of the side plates 12 and 13, a rod or shaft 27 is mounted in said plates and upon one end of this rod is mounted a pinion 28 which meshes with the pinion 25 on the impression roller and also with a pinion 29 on the upper feed roller. The said feed roller is carried by the bearings 30 on the projecting arms 32 of a U-shaped frame or bail 33 which is pivotally or rockingly mounted upon the rod 27. It will be readily understood that if the bail or frame 33 be tilted forwardly upon the rod 27, the upper feed roller will be raised so that it will clear a sheet of paper placed upon the feeding table or plate, as shown in Fig. 2, whereas, if the frame be tilted rearwardly, the feed roller will be lowered so as to hold the sheet of paper to the lower feed roller. The end of the shaft 34, which carries the upper feed roller, remote from the pinion 29, extends through an opening 35 in the side plate 13 and carries a roller 36, the function of which will presently appear.

The tension or pressure exerted by the upper feed roller on the lower feed roller may be regulated by a screw 37 mounted in a bracket 38 secured upon the upper edge of the side plate 13 and a spring 39 fitted to the lower end of the said screw 37 and bearing upon a supporting plate or arm 40 which forms a part of the bail 33 and passes around the shaft 34 so as to support the same. The lower feed roller 11 is mounted at its ends

directly in the side plates 12 and 13 and extends between the same, and the said roller is preferably provided with a continuous or uninterrupted surface whereas the upper feed roller is preferably formed of a plurality of sleeves upon the shaft 34 and spaced from each other at their ends. An inclined table or feed plate 41 is disposed between the side plates 12 and 13 and is carried by a rod or bar 42 secured in said plates. This feed plate or table 41 is inclined, as clearly shown in Figs. 2 and 3, and extends close to the lower feed roller 11. In advance of the lower feed roller and between the same and the impression roller is a feed plate 43 which extends from a point close to the feed roller downwardly to a point adjacent the impression roller where its edge is engaged by a series of guiding supports which extend under the impression roller and then upwardly in front of the same so that the paper caused to travel over the said supports will be carried to a point where it may receive an impression from the type and then carried upwardly so as to be stripped from the type and delivered at a proper point. The feed plate 43 is constructed with a plurality of openings 44 through which stop fingers 45 may project to arrest the movement of the sheet of paper and hold the same against movement until the proper time in the operation of the machine. These stop fingers 45 may be formed at the forward edge of a plate 46 extending between the side plates 12 and 13 and formed at its ends with arms 47 which are pivotally or loosely mounted upon the ends of the lower feed roller 11 or the shaft carrying said roller. A spring or springs 48 secured to the side plates 12 and 13 and bearing upwardly against the plate 46 tends to hold the stop fingers projected through the openings 44, as shown in Fig. 2. When the upper feed roller, however, is lowered, pushers 49 carried by the bearings 30 or the bail 33 will depress the plate 46 against the tension of the spring 48 and thereby move the stop fingers out of the openings 44, as shown in Fig. 3, permitting the paper to pass. The presser or guiding fingers 50 are hung upon the cross bar 51 and extend downwardly and forwardly therefrom so as to pass through the spaces between the sleeves of the upper feed roller and rest upon the feed plate 43. These presser fingers operate by gravity and yield readily to a sheet when the same is properly inserted and by bearing upon the sheet serve to hold the same evenly upon the feed plate and thereby cause it to pass properly to the impression roller. The shaft 34 carrying the upper feed roller has a fixed bearing in the arm or support 40 but at the opposite side of the machine is carried by the usual eccentric (not shown)

so that it may be adjusted to compensate for irregularity in the lower feed roller and bring opposed surfaces of the two feed rollers into exact parallelism at all times and thereby avoid paper being fed through the machine crookedly. A set screw 31 in the arm 32 holds the eccentric in the position in which it may be set and thereby maintains the adjustment of the feed roller.

10 Upon the side of the main frame, below the bearing plate 13, is a stub shaft 52 on which is loosely mounted the actuating plate 53, and a gage or adjusting plate 54 at the outer side of the actuating plate which may be held against moving off the stub shaft 52 by any well known means. The actuating plate is constructed with an arm 55 which extends below the stub shaft 52 and has its lower extremity pivoted to the rear end of the connecting rod 8, as shown clearly in Fig. 1. Upon the said arm are bearings 56 in which is mounted a worm 57 equipped with a milled head 58 to facilitate its manipulation. This worm 57 meshes with the worm teeth 59 on the lower edge of the gage plate 54 so that by rotating the worm, the relative positions of the actuating plate and the gage plate may be varied, a pointer or index finger 60 on the arm 55 extending over the edge of the gage plate so as to coöperate with a scale 61 thereon. The edge of the gage plate is concentric with the shaft 52 but at the upper part of the plate is a segmental extension 62 which at times will ride under the roller 36 and thereby lift the shaft 34 and the upper feed roller so that the paper will not be fed to the printing mechanism and it is obvious that by varying the adjustment of the gage plate, the instant when the end of the segment 62 will clear the roller 36 and permit the upper feed roller to drop may be determined and the feeding of paper thereby regulated to suit various conditions. The scale 61 is indicative of the movement of the type-bed and it will, therefore, be evident that by placing the index 60 opposite the proper point or graduation, the feeding of paper will be caused to commence at any desired point in the movement of the type-bed. The actuating plate 53 is substantially triangular above the shaft 52, as shown most clearly by dotted lines in Figs. 6 and 8, the base of the triangle being curved concentric with the shaft 52 and the plate being constructed with projections 63 and 64 at the ends of the base. These projections are adapted to alternately engage a lug 65 on the outer face of a controlling plate 66 which is also loosely mounted upon the stub shaft 52 between the actuating plate and the frame. This controlling plate 66 is constructed with an arcuate edge portion 67 which is described on a radius equal to

the radius upon which the outer edge of the segment 62 is struck so that the roller 36 may at times ride without interruption upon the said edges 62 and 67. The edge of the controlling plate is beveled, at one end of the arc 67, as shown at 68, so as to easily engage the roller 36 in the operation of the device and at the opposite end of the arc 67 is a shoulder 69 from which extends an arcuate edge 70 of greater radius than the edge 67. The projection 64 of the actuating plate 75 extends radially outward and its extremity 71 has the same radius as the arcuate edge 70 of the controlling plate, a beveled end 72 providing for an easy engagement with the part actuated thereby. The controlling plate is provided on its inner face with an arcuate shoulder 73 and a segmental rack 74 is fitted upon the said shoulder and held thereto by a keeper 75 secured to the plate and extending over the rack, as shown clearly in Fig. 7. This rack is provided at one end with a downwardly or inwardly extending plate or bracket 76 carrying a swiveled block 77 in which is mounted an adjusting screw 78, the inner end of the screw being reduced in diameter and having threads of a finer scale formed thereon, as shown at 79. This inner reduced end of the screw engages a block or post 80 which is swiveled upon the controlling plate 66 as shown most clearly in Fig. 7. By turning the screw 78, the rack 74 will be adjusted about the stub shaft 52 and, consequently, the extent to which the pinion 24 will be rotated may be varied. As the rotation of said pinion controls the adjustment of the eccentric mounting of the platen or impression roller, it is obvious that the position of the rack 74 will determine whether the copy printed will be light or heavy. A pin or other stop 81 upon the rack, by engaging against the bracket 75, will limit the adjustment of the rack so that it can not be moved to such a point that it will fail to operatively engage the pinion 24 and also prevents the adjusting screw from coming out of its bearings.

Upon the main frame, in rear of but adjacent the actuating and controlling plates, I mount the dog or locking lever 82 which has its lower end disposed slightly below the edge of the side member of the main frame and its upper end in position to engage or be engaged by the actuating plate and controlling plate. A spring 83 is disposed between the dog and the main frame and acts to move the upper end of the dog normally toward the actuating and controlling plates. The upper end of the dog is enlarged so as to provide the curved edge 84 having a radial shoulder 85 and also provide the overhanging shoulder or hook 86, the end edge of said hook being adapted to ride upon the edge 70 of the controlling plate. A roller

87 is provided upon the lever immediately adjacent the hook 86 and is arranged in the plane of the actuating plate so as to be engaged by the edge portions 71 and 72 of the same. It will be readily noted that if the shoulder 86 is in engagement with the shoulder 69, as shown in Fig. 6, the controlling plate will be prevented from moving forwardly. If, however, the projection 10 of the actuating plate be swung forwardly, the beveled edge 72 of the same will ride under the roller 87 so as to lift it and the upper end of the locking lever thereby releasing the lever from the shoulder 69 so that the projection 64, by engaging the lug 65, may move the controlling plate as shown in Fig. 8. In this position, the upper feed roller will be lifted by engagement of the roller 36 with the edges 68 and 67 of the 20 controlling plate. At the same time, the pack 74 will have rotated the pinion 24 so that the eccentric 21 will be turned to raise the impression roller.

The bracket 38 is of such form that it presents 25 bearings 88 at its ends in which is journaled a rock shaft 89 and at the inner end of said bracket are guides 90 for a slideable pin or feeler 91. This pin or feeler 91 is constructed with a lateral projection 92 engaged by the forked end of a crank 93 on the inner end of the rock shaft 89 and upon the outer end of said rock shaft is a crank 94 carrying a pin 95 at its lower end which is engaged by the notched extremity 96 of a 30 cam plate 97. This cam plate 97 is of peculiar form having a curved lower edge 98, which is adapted to ride upon a pin 99 carried by the controlling plate 66, and extending rearwardly from the cam plate is a 35 finger 100 adapted to engage the shoulder 85 upon the dog or locking lever 82. It will be understood that on the forward movement of the controlling plate the pin 99 will ride under the lower curved edge of the cam 40 and rock the same, the result being to raise the feeler 91 out of the way of paper which is being inserted.

The lower end of the lever 82 is provided with an inwardly extending projection 101 disposed beneath the side member of the main frame and carrying an upstanding pin 102. A lever or vibratory bar 103 is pivoted, as at 104, on the under side of the frame member and the rear extremity of the said 45 lever or bar is formed into a yoke or fork, the outer member 105 of which is disposed over the inwardly extending projection 101.

The inner wall or edge of the said member 105 is provided with a wedge-shaped 50 tooth 106 which is adapted to ride upon or across the pin 102 and is held to the said pin by a spring 107 secured to the frame and the said member 105. The lever or bar 103 is also provided with a transverse slot 108

engaging a pin or bolt 109 so as to limit the transverse oscillation of the member, and bolts or screws 111 are carried by the forward end of the bar or lever and pass through a longitudinal slot 110 in a stop plate 112 so that the stop plate is held to 70 but may slide on the bar. This stop plate has an upstanding lug 113 on its inner edge which is adapted to engage the depending trip 114 forming the actuating element of the ribbon feeding mechanism. A spring 75 115 having its ends secured respectively to the bar 103 and the plate 112 serves to draw the stop plate rearwardly to the extent permitted by the engagement of one of the bolts or pins 111 with the end of the slot 110. 80 The members 113 and 114 will be held in engagement until the machine completes its stroke and the stop lever 82 cannot be released so soon that the projection 113 will not be engaged by the trip 114. 85

A spring 116 is secured at its front end to the main frame and has its rear end connected with the controlling plate so that it tends to hold the said plate at the forward limit of its movement. Upon the controlling plate 66 is a block or housing 117 in which is mounted a spring-pressed plunger 118 adapted to engage a stop pin 119 on the main frame. These elements constitute a buffer mechanism which eliminates the metallic sound that otherwise would be heard when the mechanism comes to rest in its normal position.

It is thought the operation of the mechanism will be readily understood. The sheets 100 of paper are fed into the machine in the usual manner and will rest upon the feed plates 41 and 44 and against the stop fingers 45, as will be readily understood. If the paper is properly in place when the printing movement of the machine starts, the feeler 91 will be held raised by the paper and, consequently, the crank 94 will be lowered and the cam plate 97 swung about its pivot so that the finger 100 will clear the shoulder 85 of the locking lever or dog 82 and permit the dog to drop into engagement with the controlling plate. The upper feed roller 10 and the impression roller 9 will be then in their lowered positions so that the paper may be fed forward and printed. If, however, the paper should not be properly inserted, the feeler will drop through an opening in the plate 43, preferably one of the openings 44, and will, therefore, rock the shaft 89 so that the crank 94 will be swung rearwardly and the cam plate 97 thereby swung upon its pivot so that the finger 100 will be brought into a position to be engaged by the shoulder 85 and the lever or dog 82 will be thereby held out of engagement with the controlling plate. The controlling plate will then be drawn for- 110 115 120 125

ward by the spring 116 to engage the roll 36 and hold up the feed rolls 10. When the dog 82 is thus held up from engagement with the controlling plate its lower end is 5 in such position that the pin or roller 102 is off the point of the tooth 106, and the spring 107 then rocks the bar 103 so that the projection 113 is carried out of the path of the trip 114, but when the lever engages the 10 controlling plate the parts will operate as described and as shown in Fig. 9. The ribbon feeding mechanism consequently will operate only when a sheet of paper goes through the machine.

15 If the paper has been properly inserted and a printing stroke is to be made, the gage plate 54 and the actuating plate 53 will be moved forwardly simultaneously with the type-bed, the roller 36 riding upon the edge 20 of the gage plate and the controlling plate being held at rest by the dog or locking lever 82. At the proper point of the movement of the type-bed, the end of the segment 62 will clear the roller 36 whereupon said 25 roller will drop so that the upper feed roller will descend into engagement with the paper and will at once cause the paper to move forward. The controlling plate will remain at rest until the continued movement of the 30 actuating plate 53 brings the projection 64 into engagement with the lug 65, at which time the edge 72 of the actuating plate will engage the roller 87 and release the locking lever 82, whereupon the controlling plate 35 will move forward under the influence of the spring 116, the movement of the controlling plate causing the impression roller to be raised by reason of the rack 74 acting upon the pinion 24 to rotate the eccentric 21 to the lifting position. Simultaneously with this movement, the edge 67 of the controlling plate will ride under the roller 36 and lift the upper feed roller so as to restore the parts to a position which will admit a second 40 sheet of paper. As the projection 64 of the actuating plate engages the lug 65 on the controlling plate, the edge 71 will engage the roller 87 and release the dog or locking lever 82. The ribbon-feeding mechanism 45 may then operate and it will be understood that this described action of the plates does not occur until the type bed is just about to end its printing stroke. Upon the return movement of the type-bed, the controlling 50 plate will be held at rest by the spring 116 until the projection 63 of the actuating plate engages the lug 65, whereupon the pinion 24 will be rotated in the proper direction to lower the impression roller but the feed 55 roller will be held raised by reason of the segment 62 passing under the roller 36. The parts will thus be in position to permit the insertion of a sheet to be printed so that if the paper be properly inserted and resting 60

against the stop finger 45, the printing operation may be repeated. When the upper feed roller is lowered into engagement with the paper, the pushers 49 are moved downwardly by the bail 33 in which said roller is mounted and the stop fingers thereby pushed 65 out of the path of the paper, as clearly shown in Fig. 3. When the feed roller is again raised, the springs 48 project the stop fingers through the openings 44 so that they 70 will extend across the path of the paper, as 75 shown in Fig. 2.

Having thus described the invention, what is claimed as new is:

1. In a printing machine, the combination of feeding mechanism, means for controlling the feeding mechanism including a controlling plate and a locking lever arranged to at times hold said plate against movement, a feeler disposed adjacent the feeding mechanism, a cam operatively connected 80 with the feeler and disposed adjacent said controlling plate and said lever, a pin on the controlling plate arranged to ride against said cam, and interengaging means on said cam and locking lever. 90

2. In a printing machine having a paper-feeding roller, and a ribbon feeding mechanism, the combination with said roller and said mechanism, of a stop plate movable into and out of engagement with the ribbon 95 feeding mechanism, a controlling plate for raising the paper-feeding roller, a locking lever arranged to normally hold the stop plate in operative position and hold the controlling plate in inoperative position, means 100 for shifting said lever from its normal position, a feeler disposed adjacent the paper-feeding roller, and means connected with said feeler for holding the locking lever out of normal position. 105

3. In a printing machine, the combination of a feed roller, an impression roller, a controlling plate arranged to act on said rollers whereby they will be raised or lowered, an actuating plate movable past the controlling 110 plate, means whereby during a part of its movement the actuating plate will move the controlling plate, a gage plate movable with the actuating plate and arranged to at times hold the feed roller raised, and means for 115 adjusting the gage plate relative to the actuating plate.

4. In a printing machine, the combination of a feed roller, a controlling plate adapted to raise said roller, means acting constantly 120 on said plate to move it forward, a dog arranged to hold said plate against forward movement, and an actuating plate arranged to release said dog from said controlling plate, said actuating plate being constructed 125 to move the controlling plate rearward.

5. In a printing machine having a paper-feeding roller, feed controlling mechanism

comprising a controlling plate constructed to at times engage and raise the feeding roller, means tending constantly to move the controlling plate forward, means for holding said plate against forward movement, an actuating plate mounted concentrically with the controlling plate and arranged to release said holding means and constructed to at times engage the controlling plate and 10 move it rearward, a gage plate mounted concentrically with the actuating plate and movable with the same and constructed to hold the feed roller raised during a portion of its movement, and means for adjusting 15 the gage plate annularly.

6. In a printing machine having a paper-feeding roller, feed-controlling mechanism comprising a controlling plate having an edge portion adapted to ride under and raise 20 the paper-feeding roller, means connected with and acting on said plate to move the same into engagement with the paper-feeding roller, a lateral projection on said controlling plate adjacent its roller-engaging 25 edge portion, means for holding said controlling plate against forward movement, an actuating plate mounted concentrically with the controlling plate and provided at its opposite ends with radial arms adapted to engage 30 the lateral projection on the controlling plate whereby during the rearward movement of the actuating plate it will move the controlling plate, the rear radial arm of the actuating plate being constructed 35 to release the means for holding the controlling plate against movement.

7. In a printing machine having a paper-feeding roller, feed-controlling mechanism comprising a controlling plate having an 40 edge portion constructed to engage and raise the feeding roller, means connected with said plate tending constantly to move it forward, means for holding said plate against forward movement, an actuating 45 plate mounted concentrically with the controlling plate and constructed at its rear edge to release the means for holding said controlling plate, means whereby the actuating plate will move the controlling plate rearwardly, and a gage plate movable with the actuating plate and having an edge portion adapted to ride under the paper feeding 50 roller and hold the same raised.

8. In a printing machine having a paper-feeding roller, feed-controlling mechanism comprising a controlling plate having a peripheral edge portion constructed with a radial shoulder and adapted in advance of said shoulder to engage the paper feeding 60 roller and lift the same, a locking lever constructed to engage the said radial shoulder and ride on the peripheral edge portion of the controlling plate in rear of said shoulder, means tending constantly to move the

controlling plate forwardly, an actuating plate mounted concentrically with the controlling plate and provided at its rear end with a peripheral edge portion adapted to release the locking lever from the controlling plate, means whereby the actuating plate will move the controlling plate rearwardly, and a gage plate movable with the actuating plate and having a peripheral edge portion adapted to ride under the paper-feeding roller and hold the same raised.

9. In a printing machine, the combination of feeding mechanism, means for controlling and actuating the feeding mechanism including a controlling plate provided with a shoulder, a locking lever adapted to engage said shoulder, a feeler disposed adjacent the feeding mechanism, a cam plate operatively connected with said feeler, and a projection on the said cam plate adapted to engage the said locking lever.

10. In an apparatus for the purpose set forth, the combination of a feed roller, an impression roller, a controlling plate adapted to raise or lower said rollers, an actuating plate movable past the controlling plate and constructed during a part of its movement to move the controlling plate, and a gage plate movable with the actuating plate and adapted to at times hold the feed roller elevated.

11. In an apparatus for the purpose set forth, the combination of a feed roller, an impression roller, a controlling plate constructed to engage the feed roller and raise and lower the same, a rack carried by said plate, a pinion on the impression roller meshing with said rack, an actuating plate adapted at times to move the controlling plate, and a gage plate carried by the actuating plate.

12. In an apparatus for the purpose set forth, the combination of a controlling plate, a lateral projection thereon, an actuating plate movable past the controlling plate and provided at its opposite edges with projections adapted to alternately engage the projection on the controlling plate and thereby move the controlling plate, and a gage plate carried by the actuating plate.

13. In an apparatus for the purpose set forth, the combination of an actuating plate having a radial arm, a worm mounted in bearings on said arm, an indicator extending from one of said bearings, a gage plate mounted loosely concentrically with the actuating plate, and a worm formed on the edge of said gage plate meshing with the first-mentioned worm.

14. In an apparatus for the purpose set forth, the combination of a main frame, a locking lever mounted on the side of said frame, feeding mechanism, means for con-

trolling the feeding mechanism arranged to actuate said lever, an oscillatory bar mounted upon the main frame, a stop on said bar projecting upwardly therefrom, a trip adapted to impinge against the said stop, and means whereby upon movement of the lever the bar will be vibrated to remove the said stop from the path of the said trip.

15. In an apparatus for the purpose set forth, the combination with a main frame, of an oscillatory bar mounted thereon and

having an offset at one end provided with an inwardly extending tapered tooth, a trip upon the main frame, a stop yieldably mounted upon the oscillatory bar and normally in the path of said trip, a lever on the frame having a pin arranged to ride on the said tapered tooth, and feeding mechanism on the frame including means for actuating said lever.

20 In testimony whereof I affix my signature.

FRANK H. QUADE, JR. [L. S.]
